(57) **CLAIM**

The ornamental design for a vehicle mirror, as shown and described.

DESCRIPTION

FIG. 1 is a top and front perspective view of the first embodiment of a vehicle mirror, showing our new design; FIG. 2 is a bottom and front perspective view thereof; FIG. 3 is a top and rear perspective view thereof; FIG. 4 is a front elevational view thereof; FIG. 5 is a rear elevational view thereof; FIG. 6 is a left side elevational view thereof; FIG. 7 is a right side elevational view thereof; FIG. 8 is a top plan view thereof; and, FIG. 9 is a bottom plan view thereof.

The second embodiment of the vehicle headlight is mirror image of the embodiment disclosed in FIGS. 1 through 9, and is not shown.

Any broken lines represent an internal boundary of the design, the line itself and the area within form no part of the claim.
